UNITED STATES PATENT OFFICE

FELIX C. MONTUORI, OF WASHINGTON, DISTRICT OF COLUMBIA, ASSIGNOR TO BAKER & CO. INC., A CORPORATION OF NEW JERSEY

SWAGING PRESS

Application filed May 17, 1929. Serial No. 363,892.

This invention relates particularly to a press for swaging dentures. Such presses usually include a base in which is mounted a ram vertically movable, and a head to co-operate with said ram for exerting pressure upon an object placed between them. In the swaging of dentures a pot is commonly used in which is placed a die or model of the denture to be made over which is arranged the sheet of metal of which the denture is to be formed; a rubber disk is placed upon the metal sheet and a heavy cylindrical block of metal to loosely fit the pot is placed upon the rubber disk with its end projecting out of the pot beyond its top. The pot is then placed upon the ram and the ram is actuated to force said cylindrical block against the head of the press, which causes a tremendous pressure to be exerted on the rubber disk and sheet of metal so that the latter is swayed into snug contact with the die. Thereafter, the ram is lowered away from the head, the pot still containing the heavy cylindrical block is removed from the ram, and the block and other parts are lifted or dumped from the pot.

Presses of this type are also usually large and heavy, and the parts are massive so that it is difficult to set up and disassemble the presses.

One object of my invention is to provide a press of the general character described embodying novel and improved combination and arrangement of a base, ram and actuating mechanism therefor, and a head, whereby said parts shall be relatively small and easy to handle and transport and can be easily and quickly assembled and disassembled.

Another object is to provide such a press comprising a pedestal or base, a frame having a bed piece to be separably connected to said base and a head, and a ram and ram actuating mechanism in the form of a self contained unit removably mounted upon said bed piece in opposed relation to said head.

Other objects are to provide a press of this character wherein said cylindrical block is rigidly connected to said head so that it is automatically brought into and out of co-operating relation to said pot by movement

of the ram and requires no manual handling; to provide such a press which is simple and inexpensive in construction and operation and which at the same time is strong and capable of producing great pressures, for example fifty tons; and to obtain other advantages and results as will be more fully brought out by the following description.

Referring to the accompanying drawings in which corresponding and like parts are designated throughout the different views by the same reference characters,

Figure 1 is a perspective view of a swaging press,

Figure 2 is a top plan view thereof,

Figure 3 is a fragmentary end elevation with portions broken away and shown in section, and

Figure 4 is an enlarged fragmentary side elevation of the head end of the press, showing the pot and its associated parts in vertical section.

Specifically describing the illustrated embodiment of the invention, the press includes a base A which is illustrated in the form of a pedestal which comprises an integral enlarged circular disk-like foot portion 1 from which centrally projects a stem or shank 2 at the end of which opposite the foot portion 1 is a substantially rectangular top portion 3. The top portion 3 and foot portion 1 are in substantially parallel horizontal planes at right angles to the standard 2 so that with the foot portion 1 resting upon a support such as the floor, the standard 2 is disposed vertically and the top portion 3 is substantially horizontal.

Upon the base A is removably mounted a frame B which comprises a bed-piece 4 of substantially the same configuration as the top-piece 3 of the base. The bed-piece is secured to the top-piece 3 by means of bolts 5. Four tie rods 6 each have one end thereof screw threaded to the bed-piece as at 7, and said tie rods support at their other ends a head 8 secured to the tie rods between nuts 9. The head 8 is substantially parallel with the bed-piece 4 and has separately secured substantially centrally thereof by a cap screw 10, a solid substantially cylindrical block 11.

The screw 10 passes through an opening 12 in the head and a screw threaded opening 13 in the block 11. The block 11 is thus rigidly suspended from the underside of the head 8.

5 Removably mounted upon the bed-piece 4 is a self-contained ram actuating mechanism C of known construction which includes a body or casing 14 within which is movable a ram 15 by means of gearing and a screw threaded rod. The gearing is actuated in known manner through a shaft 16 by a crank 17 so that upon rotation of the crank the ram 15 is moved inwardly and outwardly of the casing 14. For applying great power to the shaft 16, the crank may have a socket 18 to removably receive a rod-like lever handle 19. The mechanism C is set upon the bed-piece 4 with the ram 15 movable vertically, studs 20 being secured in the bed-piece 4 for preventing lateral movement of the mechanism C. This mechanism is also formed with an integral handle 21 by which the mechanism may be lifted to and from the bed-piece; and to restrain rotative movement of the casing 14, I 25 may secure to the bed-piece by one of the bolts 5, an angle member 22 having a notch 23 to receive the handle 21.

Where the press is to be used for swaging dentures, a pot 24 is utilized to receive a die 30 25 from which the denture is to be made. This die is in one operation arranged between a relatively hard rubber disk 26 and a soft rubber disk 27, the sheet of metal 28 from which the denture is to be formed being laid 35 upon the die. Another hard rubber disk 29 is placed upon the soft rubber disk 27. In operation, the ram 15 is lowered so that the pot 24 may be set thereon beneath the cylindrical block 11. The ram actuating mechanism is then operated by the crank 17 to raise 40 the pot toward the block 11 so that the block enters the top of the pot into contact with the top rubber disk 29. Continued elevation of the ram then exerts great pressure on the 45 sheet of metal 28 within the pot so as to force the plate into snug contact with the die to shape the plate. Thereafter the ram actuating mechanism is operated to lower the ram, whereupon the pot is moved away from the 50 block 11 which remains suspended from the head 8. The pot is then removed from the ram and the various parts within it lifted out.

With this construction it will be observed that the base A, frame B and ram and ram actuating mechanism C are separate units which can be easily and quickly assembled into cooperative relation and disassembled therefrom. The parts are simple and relatively inexpensive in construction, but at the 55 same time enable great pressures to be exerted between the ram and the block 11, for example fifty tons. Also the base, frame and ram actuating mechanism are relatively small so that they can be easily handled and transported. The cylindrical block 11 being rig-

idly suspended from the head 8 does not require any manual manipulation according to the heretofore known methods, and said block is inserted in and removed from the pot by simple actuation of the ram 15.

70 While I have shown and described my invention as embodied in certain details of construction it should be understood that this is primarily for illustrating the principles of the invention and that the details of construction of the press may be modified or changed by those skilled in the art without departing from the spirit or scope of the invention.

75 Having thus described my invention, what I claim is:

80 1. A press for swaging dentures, comprising a base having a foot portion, an integral vertical standard and a horizontal top-piece, a frame including a bed-piece, a head and tie-rods connecting said head to said bed-piece, means for separably mounting said bed-piece upon said top-piece and said base, and a ram and ram actuating unit mounted upon said bed-piece with said ram movable toward and from said head, said unit being separate from 85 said bed-piece and applicable thereto between said tie rods.

90 2. A press for swaging dentures, comprising a base having a foot portion, an integral vertical standard and a horizontal top-piece, a frame including a bed-piece, a head and tie-rods each having one end screw threaded into 95 said bed-piece and at its other end a pair of nuts between which said head is clamped, means for separably mounting said bed-piece upon said top-piece, and a ram and ram actuating unit removably mounted upon said bed-piece with said ram movable toward and from said head, said unit being separate from 100 said bed-piece and applicable thereto between said tie-rods.

105 3. In dental swaging apparatus, the combination of a pot to receive a die and associated parts, a press comprising a frame including a head having a block rigidly suspended therefrom to freely enter said pot, a base in opposed relation to said head, a ram on said base in substantial axial alignment with said block to removably support 110 said pot and move the same toward and from said block whereby said pot slips over said block or said block is caused to enter said pot and exert pressure on the die therein, and means for actuating said ram.
